UNITED STATES PATENT OFFICE.

ERNST ELTNER, OF BASEL, SWITZERLAND, ASSIGNOR TO C. A. LORENZ, OF LEIPZIG, GERMANY.

DENTAL ARTICULATOR.

1,033,562.

Specification of Letters Patent.

Patented July 23, 1912.

Application filed March 28, 1912. Serial No. 686,800.

To all whom it may concern:

Be it known that I, ERNST ELTNER, a citizen of Basel, Switzerland, residing at Basel, Switzerland, have invented a new 5 and useful Dental Articulator, of which the following is a specification.

My invention consists of a dental articulator in which the dual movement in the joints of the lower jaw may be reproduced 10 so as to obtain complete articulation of both upper and lower dentures.

It further consists of means for exactly determining the relative positions of the centers of the lower hinge-joint and of the 15 upper joint upon the skull of the patient and for determining the amount of movement of the jaw from the most forward position to the closed biting position.

It further consists of means for applying 20 the measurements thus determined to the articulator, whereby the movements of the jaw of the patient can be accurately reproduced by the articulator.

It further consists of other novel features 25 of construction, all as will be hereinafter fully set forth.

The invention is satisfactorily illustrated in the accompanying drawing, but the important instrumentalities thereof may be 30 varied, and so it is to be understood that the invention is not limited to the specific arrangement and organization shown and described.

Figure 1 represents a perspective view of 35 my improved articulator. Fig. 2 represents a perspective view of the device for securing the measurements of the movement of the lower jaw during mastication. Fig. 3 represents a view of such device applied to 40 the jaw of a patient. Fig. 4 represents a perspective view of the articulator with the measuring device attached to make a cast of the lower jaw. Fig. 5 represents a view of the protractor for ascertaining the center of the upper joint. Fig. 6 represents a 45 perspective side view of the articulator with the casts of the jaws in place, illustrating the application of the card to the articulator to determine the center of the upper joint of the jaws. Fig. 7 represents 50 a view of one of the disks, with the intermediate link removed. Fig. 8 represents a view of said disk and the intermediate link. Fig. 9 represents a section through the rear 55 end of a limb of the upper jaw-portion, one

of the disks, one of the screw-bolts and the nut securing the same.

Similar numerals of reference indicate corresponding parts in the figures.

Referring to the drawing, the numeral 1 60 indicates the upper jaw-portion of the articulator, which is substantially triangular and has a forwardly projecting portion, 2, at the apex of the triangle. The upper jaw-portion has transverse bores, 3, at the 65 rear ends of its limbs, and the smooth portions of screw-bolts, 4, fit in said bores and have radially projecting pins, 5, slidable in slots, 5*, in the bores, whereby turning of the bolts in the bores is prevented. Arm 70 members such as disks, 6, are eccentrically secured to turn upon the outer ends of the bolts, and nuts, 7, are fitted upon the threaded inner ends of the bolts to clamp the disks against the upper jaw-portion of 75 the articulator. Holes, 8, or depressions are formed in the disk along a diameter passing through the pivot-point or turning center of the disks, and said holes are spaced at predetermined distances, such as 80 two millimeters apart, and the distance from the turning center is preferably indicated at each hole, as seen in Fig. 7. Intermediate links, 9, have pins, 10, at their 85 ends, which pins are adapted to engage the holes in the disks, and said links have each a series of holes or depressions, 11, spaced at predetermined distances, such as two millimeters apart, and also preferably indicated by numerals, as seen in Fig. 9, marking 90 the distance of each hole from the pivot-points of the links, viz., the pins. Stops, 12, are secured on the faces of the disks to limit the swing of the links.

The lower jaw-portion, 13, of the articulator has a triangular body-portion, 14, and upwardly projecting and slightly rearwardly inclined limbs, 15, formed with screw-threaded transverse bores in their upper ends, through which pass pointed screws, 16, having locking nuts, 17, upon their outer portions. The pointed inner ends of said screws are adapted to engage 95 in the holes in the intermediate links.

An arched frame, 18, has a downwardly projecting screw, 19, upon the middle of its straight front bar, and said screw has a clamping nut, 20. Blocks, 21, slide with their horizontal bores, 22, upon the straight 100 and parallel limbs 23, of the frame, and 105

bars 24, slide in vertical bores 25, in the blocks, said vertical bores intersecting the sides of the horizontal bores. Screws, 26, are threaded in the outer portions of the blocks to clamp the latter on the limbs of the frame and the vertical bars in their bores. Screws, 27, are threaded in the upper ends of the vertical bars and have pencil-points, 28, in their inner ends. An impression-spoon, 29, capable of containing wax or other plastic material, and of a shape corresponding to that of the lower jaw, has a perforated shank, 30, which may be secured upon the screw 19 and by the nut 20. The lower jaw-portion of the articulator has a flat tongue, 31 projecting from its apex, and a slide, 32, having an upright flange, 33, slides upon the same. The forwardly projecting portion 2 of the upper jaw-portion of the articulator has a vertical bore in which a rod, 34, slides, being adjustably secured by a set-screw, 35. The lower end of said rod has a blade, 36, formed with a triangular point which may engage the flange of the slide upon the lower jaw-portion.

In practice, the ordinary impression and cast is made of the upper jaw. An impression in wax or other plastic material of the lower jaw is thereupon taken in the impression-spoon which thereupon is secured in the arched frame by means of the screw and nut upon the same. The frame is thereupon manually adjusted with the impression resting upon the lower jaw and the pencil points are adjusted by moving the blocks and the vertical bars so as to bring them in register with the moving center of the lower mandible joint and so as to nearly touch the cheek of the patient. A card is now inserted between the cheek of the patient and the pencil-points, and a mark is made on the card at its front edge, registering with some prominent point of the upper jaw of the patient, a tooth, if such is there, or any prominent point which may be identified on the cast of the upper jaw. The patient thereupon moves the lower jaw from the biting or closed position to the forward position, and the pencil point will mark on the card an arc, corresponding to the arc described by the lower hinge-joint of the jaw on the center of its rest upon the skull. The rearmost end of such arc will indicate the extreme of the closed position of the jaw. The center of such arc may now be ascertained by a protractor 37 and marked on the card. The arched frame and the impression spoon with the impression of the jaw and whatever teeth may be, are now removed from the mouth of the patient and the frame is pivoted upon the outer ends of the pointed screws connecting the upper and lower-jaw portions the pencil-screws being removed, and said former

portion being tilted backward. A cast in plaster is taken in the impression-spoon. A quantity of plaster is now placed upon the lower jaw-portion, and the cast in the impression-spoon is tilted over, together with the arched frame, to adhere to said mass of plaster. The arched frame and impression-spoon with its impression are now removed from the articulator and the upper jaw-portion is tilted forward with its plaster cast to take the bite whereupon such upper cast is secured in said upper jaw portion by plaster. The nuts upon the trunnion-screws 4 of the disks are now loosened and one card is placed with the mark on its forward edge pointing to the place on the cast of the upper jaw with which such mark registered in the jaw of the patient. The cards are folded or cut on a line drawn through the rear extreme of the arcs and the centers of such arcs, as found by the protractor, and the intermediate links are rocked to bear against the rear stops upon the disks. The disks which have been loosened by loosening the nuts upon the trunnion-screws, 4, are now moved until the edge of each intermediate link has its edge at the oblique edge of the card,—the pivot pin being at the center of the arc and the edge of the link against the rear end of the arc, whereupon the nuts upon the trunnion-screws are tightened to secure the disks in their adjusted positions. The pivot-pins of the intermediate links have been adjusted in holes in the disk, according to the reading upon the protractor of the radius of the arc upon the card. Thus, if for instance, such radius is 20 mm. for the right side and 14 mm. for the left side, the pivot pin is fitted in the hole marked 20 of the right-hand disk and in the hole marked 14 in the left-hand disk. The points of the pivot-screws upon the lower jaw-portion are adjusted to engage the holes in the intermediate links similarly marked. The adjustable rod in the forward projection of the upper jaw-portion is adjusted to hold said latter portion in biting position when the point of the rod rests upon the flanged slide, the inclined edge of the blades sliding upon the flange giving a relative movement of the jaw-portions of the articulator corresponding to the rearward movement of the human lower jaw when closing tightly into biting position. The plaster cast upon the lower jaw has now the proper position and relative distance from the cast in the upper jaw, whereupon the work of forming the dentures may be proceeded with in the articulator with the same accuracy as in the mouth of the patient, the movements of the joints in the articulator exactly reproducing the movements of the jaws of the patient.

The lower joints in which the jaw move-

ment of mastication takes place find their counterparts in the joints between the pointed pivot-screws and the holes in the intermediate links, and the upper joints

5 which permit of the forward and back movements of the jaw, find their counterparts in the pivot-pins of the intermediate links turning in the holes in the disks. The articulator thus has both the hinge-movement and the swinging movement of the human jaw and may be accurately adjusted to the dimensions of the patient's jaw.

Having thus described my invention what I claim as new and desire to secure by Letters Patent, is:—

1. In a dental articulator, an upper jaw-portion adapted to receive the plaster cast of the upper jaw, a lower jaw-portion adapted to receive the plaster cast of the lower jaw, arm members adjustably pivoted to the sides of one of said jaw-portions, intermediate links having radially adjustable support upon said arm-members, and pivot-members upon the other jaw-portion and 25 having adjustable pivot-support upon said links.

2. In a dental articulator, an upper jaw-portion adapted to receive the plaster cast of the upper jaw, a lower jaw-portion 30 adapted to receive the plaster-cast of the lower jaw, arm members adjustably pivoted at the sides of the upper jaw portion, intermediate links having radially adjustable support upon the faces of said arm-members, and pivot-members upon the lower 35 jaw-portion and having longitudinally adjustable pivot-connection with said links.

3. In a dental articulator, an upper jaw-portion adapted to receive the plaster cast 40 of the upper jaw, a lower jaw-portion adapted to receive the plaster cast of the lower jaw, arm members adjustably pivoted at the sides of one of said jaw-portions and each formed with a diametrical series of 45 holes, intermediate links having each a pin at one end engaging one of the holes in the arm-members, and each formed with a longitudinal series of holes, and pivot-points in the sides of the other jaw-portion and 50 each engaging a hole in an intermediate link.

4. In a dental articulator, an upper jaw-portion adapted to support the plaster cast 55 of the upper jaw, a lower jaw-portion adapted to support the plaster cast of the lower jaw, arm-members adjustably pivoted at the sides of the upper jaw-portion and formed with a diametrical series of holes, intermediate links having each a pin at its 60 end adapted to engage one of the holes in the arm-member and each formed with a

longitudinal series of holes, and pivot-points in the sides of the lower jaw-portion and each engaging one of the holes in an intermediate link.

65

5. In a dental articulator, an upper jaw-portion adapted to support the plaster cast of the upper jaw and formed with transverse bearings in its rear ends, a lower jaw-portion adapted to support the plaster cast of the lower jaw and formed with screw-threaded bores in its rear ends, bolts in the bearings of the upper jaw-portion, clamping nuts upon said bolts, disks eccentrically pivoted upon the ends of said bolts and each 70 formed with a diametrical series of holes passing through the pivot-center and with stops upon its face, intermediate links having pins at their ends adapted to engage the holes in the disks and each formed with 75 a longitudinal series of holes, pointed screws in the bores of the lower jaw-portion and having their points adapted to engage the holes in the links, and locking nuts upon 80 said screws.

85

6. An arched frame formed with straight parallel limbs, means for securing an impression spoon at the middle of the transverse bar of the frame, blocks slideable upon the limbs of the frame, bars vertically sliding in said blocks, means for adjusting the blocks upon the limb of the frame and the bars in said block, and pencil-holders transversely adjustable in the ends of the vertical bars.

95

7. In a dental articulator, an upper jaw-portion adapted to support the plaster-cast of the upper jaw, a lower jaw-portion adapted to support the plaster cast of the lower jaw, arm-members adjustably supported at the sides of the upper jaw-portion, intermediate links having radially adjustable support upon the faces of said arm-members, pivot-screws transversely threaded in the rear ends of the lower jaw-portion 100 and having their inner ends engaging the links and having laterally projecting outer ends, an arched frame having straight parallel limbs, an impression-spoon secured at the middle of the transverse bar of the 110 frame, blocks slideable upon the limbs of the frame, bars vertically slideable in said blocks and having transverse holes in their upper ends engaging the outer ends of the pivot-screws, and means for adjusting the blocks 115 upon the limbs of the frame and the bars in the blocks.
